UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

STORAGE BUILDING.

1,349,664.

Specification of Letters Patent. Patented Aug. 17, 1920.

Application filed August 8, 1919. Serial No. 316,183.

To all whom it may concern:

Be it known that I, FERNAND E. D'HUMY, a citizen of the United States, and resident of Englewood, county of Bergen, and State of New Jersey, have invented certain new and useful Improvements in Storage Buildings, of which the following is a specification.

This invention relates to improvements in building structures, and more particularly to storage buildings, the improvements being especially applicable to garage structures for storing motor vehicles.

One object of the invention is to provide a storage building so constructed that vehicles may travel under their own power from floor to floor of the building to and from storage spaces on the various floors.

Another object of the invention is to provide a storage building having storage space on its several floors and so constructed that vehicles may travel under their own power from floor to floor to and from storage spaces on the several floors with the vehicles forming the ascending and descending streams of traffic moving in the same direction over the several floors.

A further object of the invention is to provide a compact construction for garages in which a maximum number of vehicles may be stored in a structure of given size and in which numerous vehicles may readily travel to and from their storage spaces at the same time without confusion and without interference between ascending and descending vehicles, the ascending and descending streams of traffic moving in distinct zones.

In the drawings: Figure 1 is a horizontal section on the line I—I of Fig. 4 illustrating one construction embodying the invention;

Fig. 2 a vertical sectional view on the line II—II of Fig. 1;

Fig. 3 a vertical sectional view on the line II—II of Fig. 1;

Fig. 4 a vertical sectional view on the line IV—IV of Fig. 1;

Fig. 5 a horizontal sectional view on the line V—V of Fig. 8 illustrating another construction embodying the invention;

Fig. 6 a vertical sectional view on the line VI—VI of Fig. 5;

Fig. 7 a vertical sectional view on the line VII—VII of Fig. 5; and

Fig. 8 a vertical sectional view on the line VIII—VIII of Fig. 5.

Referring to Figs. 1 to 4, 1 designates the outer walls of the building and 2 designates an intermediate partition or dividing wall. The outer walls 1 are provided with suitable window openings 3 and also with suitable doorways 4 permitting access to the ground floor 5 of the building. The upper floors of the building are arranged in two series, the series of floors 6 at one side of the dividing wall 2 being spaced equal distances apart 60 and the lower floor 6 being spaced above the ground floor 5 a distance equal to the distance between the floors of this series. The series of floors 7 at the opposite side of the dividing wall 2 lie in planes midway between 65 the planes of the floors 6, the lowermost floor 7 lying in a plane midway between the planes of the ground floor 5 and the lowest of the series of floors 6. That portion of the ground floor 5 underlying the series of floors 70 6 forms in effect the lowest of two vertical series of floors, the floors of one of which series are arranged in planes intermediate the planes of the floors of the other series.

Adjacent one of the outer walls of the 75 building is a vertical series of similarly inclined superposed ramps 8 each of which extends through the dividing wall 2 an equal distance on each side of said wall and connects one of the series of floors 7 with the 80 next lower one of the series of floors at the opposite side of the dividing wall. Adjacent the opposite side wall of the building is a vertical series of ramps 9, inclined in a direction opposite to the inclination of the 85 ramps 8, extending through the dividing wall and connecting each floor 7 with the next higher one of the floors 6. Alongside the series of ramps 8 is a series of ramps 10 extending through the dividing wall inclined in the same direction as the ramps 9 and connecting each floor 7 with the next 90 higher one of the floors 6. Alongside the series of ramps 9 is a vertical series of ramps 11 extending through the dividing wall 2, said ramps 11 being inclined in the same direction as the ramps 8, and connecting each of the floors 7 with the next lower one of the floors at the opposite side of the wall 2.

Each of the floors 6 and 7 has an unobstructed passage or driveway communicating at one end with one of the ramps 8 and one of the ramps 10 and communicating at its opposite end with one of the ramps 9 and 110

one of the ramps 11. Each floor 6 and 7 is also provided with storage space at one side of the driveway along the wall 2 between the ramps 10 and 11 and also with storage space 5 at the opposite side of the driveway between the driveway and the outer wall of the building opposite the dividing wall.

The storage spaces on each floor may be subdivided in any suitable manner. In the 10 construction shown, which is especially designed for use as a garage, the two main storage spaces on each floor are divided by relatively low partitions or guard rails 12 into storage spaces or compartments for 15 individual vehicles.

With the construction above described it will be obvious that a plurality of vehicles forming two lines of traffic may move in the same direction and in different zones 20 from floor to floor and that, if the vehicles forming one line of traffic move from floor to floor by way of the two series of ramps 8 and 9 and the vehicles forming the other line of traffic move from floor to floor by 25 way of the two series of ramps 10 and 11, the vehicles forming one line of traffic will ascend from floor to floor and the other vehicles will descend from floor to floor.

In the construction shown in Figs. 5 to 8, 30 inclusive, a different relative arrangement of the four series of ramps is shown, the two series of ramps 8 and 11 being arranged at opposite sides of the building and the two series of ramps 9 and 10 being located 35 alongside each other at the center of the building.

It will be obvious that the four series of ramps may be arranged at various other points along the wall 2, if desired, and that 40 in large buildings a plurality of groups of four series of ramps each may be employed if desired.

What I claim is:

1. A building structure comprising outer 45 walls, a series of superposed floors overlying a part of the ground area within the outer walls, a second series of superposed floors lying in planes intermediate the planes of the first series of floors and overlying 50 another part of the ground area within the outer walls, a pair of ramps connecting each floor of the first series with the next higher floor of the second series, and a pair of ramps connecting each floor of the first 55 series with the next lower floor of the second series.

2. A building structure comprising outer walls, a series of superposed floors overlying a part of the ground area within the outer 60 walls, a second series of superposed floors lying in planes intermediate the planes of the first series of floors and overlying another part of the ground area within the outer walls, two vertical series of similarly 65 inclined ramps one ramp of each of which

series connects one of the first series of floors with the next higher one of the second series of floors, and two vertical series of ramps inclined oppositely to the first-mentioned ramps one of each of which series connects 70 one of the first series of floors with the next lower one of the second series of floors.

3. A building structure comprising outer walls, a series of superposed floors overlying a part of the ground area within the outer 75 walls, a second series of superposed floors lying in planes intermediate the planes of the first series of floors and overlying another part of the ground area within the outer walls, two vertical series of similarly 80 inclined ramps one ramp of each of which series connects one of the first series of floors with the next higher one of the second series of floors, and two vertical series of ramps inclined oppositely to the first-mentioned ramps one of each of which series connects 85 one of the first series of floors with the next lower one of the second series of floors, the four vertical series of ramps being so arranged that vehicles ascending from 90 floor to floor and vehicles descending from floor to floor may move in the same direction between independent pairs of oppositely inclined ramps communicating with each floor.

4. A building structure comprising outer 95 walls, a series of superposed floors overlying a part of the ground area within the outer walls, a second series of superposed floors lying in planes intermediate the planes of the first series of floors and overlying another part of the ground area within the outer walls, two vertical series of similarly 100 inclined ramps one ramp of each of which series connects one of the first series of floors with the next higher one of the second series of floors, and two vertical 105 series of ramps inclined oppositely to the first-mentioned ramps one of each of which series connects one of the first series of floors with the next lower one of the second series of floors, the four vertical series of ramps being so arranged relatively to each other that up and down traffic in the building may move in the same direction and in separate zones.

5. A building structure comprising outer walls, a series of superposed floors overlying a part of the ground area within the outer walls, a second series of superposed floors lying in planes intermediate the 110 planes of the first series of floors and overlying another part of the ground area within the outer walls, two vertical series of similarly 115 inclined ramps one ramp of each of which series connects one of the first series of floors with the next higher one of the second series of floors, and two vertical 120 series of ramps inclined oppositely to the first-mentioned ramps one of each of which series connects one of the first series of floors with the next higher one of the second series of floors, and two vertical 125 series of ramps inclined oppositely to the first-mentioned ramps one of each of which series connects one of the first series of floors with the next higher one of the second series of floors, and two vertical 130 series of ramps inclined oppositely to the first-mentioned ramps one of each of which series connects one of the first series of floors with the next higher one of the second series of floors.

of floors with the next lower one of the second series of floors, said four series of ramps being arranged with two series of oppositely inclined ramps located in alignment with the remaining two series of ramps and intermediate the same.

6. A building structure comprising outer walls, a series of superposed floors overlying a part of the ground area within the outer walls, a second series of superposed floors lying in planes intermediate the planes of the first series of floors and overlying another part of the ground area within the outer walls, two vertical series of similarly inclined ramps one ramp of each of which series connects one of the first series of floors with the next higher one of the second series of floors, and two vertical series of ramps inclined oppositely to the first-mentioned ramps one of each of which series connects one of the first series of floors with the next lower one of the second series of floors, two of said series of ramps of opposite inclination being located at opposite sides of the other two series of ramps.

7. A building structure comprising outer walls, a series of superposed floors overlying a part of the ground area within the outer walls, a second series of superposed floors lying in planes intermediate the planes of the first series of floors and overlying another part of the ground area within the outer walls, two vertical series of similarly inclined ramps one ramp of each of which series connects one of the first series of floors with the next higher one of the second series of floors, and two vertical series of ramps inclined oppositely to the first-mentioned ramps one of each of which series connects one of the first series of floors with the next lower one of the second series of floors, said four series of ramps being grouped in pairs located at opposite sides of the building and the two series of ramps forming each group being of opposite inclination.

8. A building structure comprising outer walls, a series of superposed floors overlying a part of the ground area within the outer walls, a second series of superposed floors lying in planes intermediate the planes of the first series of floors and overlying another part of the ground area within the outer walls, two vertical series of similarly inclined ramps one ramp of each of which series connects one of the first series of floors with the next higher one of the second series of floors, two vertical series of ramps inclined oppositely to the first-mentioned ramps one of each of which series connects one of the first series of floors with

the next lower one of the second series of floors, said four series of ramps being grouped in pairs located at opposite sides of the building and the two series of ramps forming each group being of opposite inclination, and a dividing wall extending between the two groups of ramps midway the length of the ramps, each floor of each series having an unobstructed passage between the two groups of ramps and storage space at opposite sides of the passage.

9. A building structure comprising outer walls, a series of superposed floors overlying a part of the ground area within the outer walls, a second series of superposed floors lying in planes intermediate the planes of the first series of floors and overlying another part of the ground area within the outer walls, two vertical series of similarly inclined ramps one ramp of each of which series connects one of the first series of floors with the next higher one of the second series of floors, two vertical series of ramps inclined oppositely to the first-mentioned ramps one of each of which series connects one of the first series of floors with the next lower one of the second series of floors, and a dividing wall between the two series of floors, said four series of ramps extending through the dividing wall, and each floor of each series being provided with an unobstructed passage between the ends of the ramps communicating therewith and having storage space at both sides of said passage.

10. A building structure comprising outer walls, a series of superposed floors overlying a part of the ground area within the outer walls, a second series of superposed floors lying in planes intermediate the planes of the first series of floors and overlying another part of the ground area within the outer walls, a dividing wall between the two series of floors, a plurality of series of superposed ramps extending through the dividing wall and communicating at their ends with the two series of floors, the ramps of certain of said series inclining downwardly from one series of floors and the ramps of the remaining series inclining downwardly from the other series of floors, each floor intermediate the upper and lower floors of the building having an unobstructed passage communicating with ramps of four different series two of which are inclined in one direction and the other two of which are inclined in the opposite direction.

In testimony whereof I hereunto affix my signature.

FERNAND E. D'HUMY.
